SHINGLE

John R. Brown, Woodmont, and Clinton I. Read, Stratford, Conn., assignors to Tilo Roofing Company, Inc., Stratford, Conn., a corporation of Delaware

Application September 9, 1949, Serial No. 114,792

4 Claims. (Cl. 108—7)

1

This invention relates to an improved shingle of the flexible type, and more in particular to an improved construction of such shingles wherein, after having been laid on a roof or siding of a home, warehouse, or other buildings, they will not be torn by reason of the ordinary and extra ordinary fluxations of the weather elements, like heavy winds and gales.

The invention further pertains to an improved construction of flexible shingles which provides for a relatively small or limited movement in a predetermined direction of the free or weather end of a shingle, thus preventing tearing of the shingle. The invention further pertains to an improved distribution of forces tending to tear all or partially, the shingles from their laid positions. With the improvement herein, the life tenure of the shingles in operation is greatly lengthened while still maintaining the shingle as originally designed for satisfactory, weatherproofing functions.

One of the features of this invention is to incorporate in the structures of shingles, known as the asphalt type shingle, additional or recesses or openings of specific outlines and having the recesses formed in the shingle in particular positions whereby the shingle resists being torn under bad or gale weather conditions.

Another feature of this improved invention is to so design the added openings or recesses and construct the shingles with these openings specifically placed or positioned so that any two co-operating portions of the shingles after being laid will function without tearing during adverse weather conditions.

Another feature of this invention is the provision of a novel construction of a flexible shingle which has assembly positioning indicators, and which has tabs that interlock with the shingles of the adjacent course or layer, and which has definite outlined cut-away supplemental recesses and notch type cutouts all particularly positioned so as to prevent tearing of the shingle tabs when high speeds of air pass over the shingles as laid on the roof or sidings.

In considering the structure of the shingle, the tabs may be referred to as wings or ears or extensions for interlocking purposes. In addition, the recesses above mentioned may also be referred to as slits or slots or openings or notches, as formed in the shingles.

In general, the invention provides for an improved composition shingle of the rhombus form adapted to be laid with one corner to the weather and having the anchoring tabs engaging shingles in the adjacent lower courses.

These improved anchoring tabs and the various type of recesses, both main and supplemental recesses, and notches, are all provided to permit novel assembly of the shingles on the roofs and

sidings so as to prevent the tearing of these tabs by reason of pulling forces developed by high speed winds, such as gales, passing over the shingles. With the improved structure herein, the forces which have a tendency to tear the tabs are distributed at four or six points and thus the forces which ordinarily would tear the tabs are greatly reduced in value at any one point that they are less than the forces required to tear a shingle of this type.

It is to be understood that there may be one or more of these anchoring tabs employed on each shingle and that the tabs may be of any particular shape, so long as they function to engage the shingles of the lower adjacent course. It is preferred that the tabs be formed in shingles of the rhombus type and that usually the tabs come within the outside outline of the shingles.

One of the main features of the invention is the provision of an improved design of shingle with anchoring tabs which have various recesses and notches therein that will allow the free or exposed end of the shingle to have a limited movement before it is stopped or locked against further movement by positively engaging the shingles in the adjacent course. This improved design provides for the distribution of the outward pulling forces developed by high winds so that the actual forces on the tabs themselves when locked against further movement are not sufficient to tear.

Wind tunnel tests of air speeds up to 92 miles per hour have been made on the improved shingles of the type herein with one corner laid to the weather and having improved means for anchoring this weather exposed end of the shingle.

The results of these wind tunnel tests show that there is a negative pressure or vacuum created over the shingles tending to pull them away from the roof. This pull will be hereinafter termed a "load" on the shingle. Various pitot tube measurements during the tests did show the positions of greater or less negative pressures. The negative pressures are largely produced in proportion to the air velocity.

From these tests and with particular reference to the prior class of interlocking shingles where there was no predetermined allowable "free" movement by having the tabs held in fixed and unmovable position, it has been observed that as the velocity of the air is slowly increased, a slight perceptible bulging or outward deformation of the shingle occurs. As the air velocity still further increases, resulting in larger or greater load, the bulging force becomes greater and greater until a final amount of bulging occurs, whereupon, further increase in air velocity causes no further outward or upward deformation. As air velocity continues to increase, a point is reached

where the tabs are torn from the body of the shingle, or pulled from their interlocking position. In the case of such rigidly fixed interlocking shingles with no allowable limited movement, the amount of this bulging or upward deformation, is largely dependent upon the elastic and flexible properties of the shingle.

However, when the principles of this invention were incorporated in the design of the interlocking shingle permitting a slight but definite degree of "free" movement of the locking tabs, much greater air velocities were tolerated without damage to the locking tabs or the withdrawing of them from their locked position. Actually in a wind tunnel test with one of the improved forms of interlocking shingles arranged to provide slight movement of the tabs, though substantial amount of bulging occurred, the shingles were subjected to the maximum wind tunnel velocity of 92 miles per hour without tearing the tabs or withdrawing them from their locked position with adjacent shingles. During the course of this experiment, it was observed that at about 60 miles per hour the center of the shingle had been deformed outward or upwards from the roof about 1" due to the movement permitted, and remained in this position throughout the balance of the test. Through the application of engineering principles this phenomenon has been found to be due to a substantial reduction in internal stress in the shingle and to a redistribution of the distorting forces, thereby reducing these forces at any one point.

By reason of these tests and the considerations of the various forces, an improved design of shingle has been provided wherein there is allowed a limited movement of the weather end of the shingle before being locked against further movement. Also, these tests taught the advisability of providing supplemental recesses or slots and additional notches specifically placed whereby a limited movement of the weather end of the shingle is allowed before this weather end becomes locked against further movement. The forces or loads created by the negative pressure on the shingles by reason of gale weather or otherwise, are distributed so that the actual pulling forces on the tabs after they have had the limited or preliminary movement, are reduced to such an extent that they will not tear the tabs from the main body of the shingle. These supplemental recesses and additional notches, and the like, are formed in each shingle body in a preferred manner so that the axes of each of these supplemental recesses or notches bear a very definite relation to lines joining some of the fastening means or nails which hold the shingle to the roof. For instance, if a line is drawn between the two lower fastening means or nails holding each shingle to the roof, then the axes of the supplemental recesses at the bottoms of the main recesses forming the tabs are positioned to be substantially perpendicular to the line between the two nails.

Another feature of the invention is the provision of an improved shingle in which the internal stresses in the shingle, particularly at the locking tabs, will be distributed and reduced and minimized so as to prevent the wind loads from tearing off the locking tabs or pulling the tabs out of position with the adjacent or underlying shingles.

The foregoing features and other features of the invention will be noted in the detailed de-

scription below when considered in connection with the attached drawings wherein:

Fig. 1 is a plan view of an improved shingle of the flexible type including the several features of this invention;

Fig. 2 is a plan view of a rhombus type shingle which includes one of the features of this invention;

Fig. 3 is a plan view of another form of flexible shingle which includes some of the features of this invention;

Fig. 4 is a plan view of two laid courses of the improved designed and constructed shingles and showing the cooperation of the shingles in one course with those in an adjacent course;

Fig. 5 is a sectional view taken on the line 5—5 of one of the shingles shown in Fig. 4 after deflection caused by wind load;

Fig. 6 is a graphical stress diagram representing the reduced intensity of internal stresses of the improved shingle illustrated in Fig. 5;

Fig. 7 is a graphical stress diagram derived from space diagram Fig. 11, showing a reduced tearing force affecting any of the improved shingles in Fig. 4;

Fig. 8 is a plan view of a series of shingles without the improvements and laid as the shingles in Fig. 4;

Fig. 9 is a sectional view taken on the line 9—9 of Fig. 8, after deflection caused by wind load;

Fig. 10 is a graphical stress diagram representing excessive stresses in the prior shingles illustrated in Fig. 8;

Fig. 11 is a space diagram showing in conjunction with graphical stress diagram Fig. 7, a relatively large tearing force developed in the shingle assembly of Fig. 8;

Figs. 12, 13, 14, 15, 16 and 17 illustrate different types of slits and recesses which are formed in the improved shingles illustrated in Fig. 4 and the cut-away portions or recesses are shown in different contours desirable for shingles applied to a roof and to reduce tearing forces when the load line may take one of any of the directions of the axes of the contours of the recesses.

Referring now to these drawings, the improved shingle 26 includes the several features of the invention as applied to a substantially diamond shaped flexible asphalt type shingle. This shingle is provided with the tabs 27 and 28 as formed from the body of the original shingle, and provides main recesses 29 and 30 between the tabs and the body. In addition, the design of the new shingle provides for supplemental recesses 31 and 32, preferably formed at or near the bottoms of the main recesses 29 and 30. Other types of recesses or notches 34 and 35 are formed in the sides of the shingle in which the tabs are formed. Preferably, these notches 34 and 35 are located or formed near the corners of the shingle which are adjacent to the corner where the tabs 27 and 28 are formed. In addition, the shingle is designed to have locating or indicating marks 37 and 38 preferably at or near the corner opposite the corner having the tabs 27 and 28. These locating marks are employed in laying the shingles in courses so as to allow the weather ends of the shingles to have a predetermined limited movement before the movement is stopped and the shingle locked against further movement.

The shingle 39 noted in Fig. 2 is a rhombus type of shingle having a different outline than the shingle 26 illustrated in Fig. 1. The improve-

ments and functions of this type of shingle are the same as those of the shingle in Fig. 1. Likewise, the shingle 40 shown in Fig. 3 is a "square" type of shingle, and is provided with supplemental recesses 31 and 32 and with notches 34 and 35 so that this type of design may be properly locked with adjacent shingles in the next lower course. Thus, it will be noted the improvements in the diamond shaped shingle may be readily incorporated in other designs of shingles.

Referring now to Fig. 4, there is shown a portion of assembled shingles on a roof in three courses. Shingles 46, 47 and 48 are laid in one course and shingles 49 and 50 are two of the shingles in the next higher course, and shingle 51 is illustrated as one of the shingles in the still higher course. This assembly in Fig. 4 illustrates the cooperation of shingles with the improvements of this invention incorporated in each. It will be noted that shingle 46 is fastened to the roof by nail 52, and shingle 47 is fastened to the roof by nails 53, 54, 55 and 57. Often times instead of employing two fastening means as nails 54 and 56, one fastening means 58 at this point may be substituted. It will be further noted that shingles 49 and 50 are fastened in position by nails 59, 60, 61 and 62. It will be noted that tabs 27 and 28 of shingle 49 interlock under shingles 46 and 47. In so assembling shingles 49 and 50, the supplemental recesses 31 and 32 preferably cooperate and align with notches 34 and 35 and leave a total distance of approximating $\frac{1}{8}$ " between the bottoms of the notches and the bottoms of the supplemental recesses. This distance or space allows the free or weather end of shingle 49 to move upwardly a predetermined limited distance before the bottoms of supplemental recesses 31 and 32 definitely engage the bottoms of notches 34 and 35 in shingles 46 and 47 and are then locked against further upward movement. As noted before, the upward movement is developed by the negative pressure load on shingle 49 which causes it to bulge as indicated in Fig. 5. Such a load also develops in the other shingles when the roof or siding is being subjected to winds of high intensity.

In the laying of a roof or siding with the improved design shingle in its several courses, each shingle will have an exposed weather end. It will be noted in reference to the laying of shingles 49 and 50 that there is the fastening means or nails 59, 60, 61 and 62 at the three corners. As negative pressure or load develops by passage of high wind and creates a load force indicated by the arrows 66 in Fig. 5, it pulls the shingle against the resisting nails 59, 60, 61 and 62 with a directional force indicated by arrow 67. As this force 66 increases, the weather end of the shingle will move through its limited movement and then be locked in position to the adjacent shingles in the next lower course and the locking tabs will then accept their portions of the load 66 and act in the opposite direction in accordance with force arrow 68 to help resist the load pull. When this interlocking takes place each shingle may be considered to have a four-point distribution of the load 66. However, a great deal of this load is originally taken up and absorbed by nails 59, 60, 61 and 62 so that when the locking tabs are locked in position and accept their part of the load, there previously has been such a distribution of the load that the force against the tabs 27 and 28 is relatively small and is less than a force required to tear this type of shingle. It will be noted that when

nails 60 and 61 are substituted by a single nail like 58, that there is a very definite type of three-point support to receive and resist the beginning of load 66, and when the tabs 27 and 28 begin to take their load, then there is a definite four-point support to distribute the load 66. With this improved shingle, the load 66 is so distributed that no tearing of the tabs occurs. This type of distribution of the load was proved out by the wind tunnel tests. There is often a stretching of the internal structure of each shingle as the load 66 increases. This stretching usually develops between the three-point fastening before the tabs 27 and 28 come into resisting position. This is another reason why the tearing forces against tabs 27 and 28 are reduced.

Shingle 51 and the shingles in its course cooperate with shingles 49 and 50 in the same manner as the description in regard to the cooperation of shingle 49 with shingles 46 and 47. In this instance where the weather end is free to move there is a so-called "determinate" structure made up of only three fastening points at the start of the load and the fourth resisting member or point comes into operation only after a predetermined limited movement and the tabs are brought into locked position. With this situation, distribution of the load becomes proportional to the elongation or stretch in the shingle over the three corners at the beginning and then the fourth corner takes its relatively small proportional part of the load.

In order to bring out compared values of the improvements in this newly designed shingle, reference is made to Fig. 8 where the old type of shingle assembly is shown with the bottoms of main recesses 29 and 30 of shingle 70 actually engaging shingles 71 and 72. It will be noted there is no free movement of the weather end of shingle 70 and when a weather load 73, Fig. 9, actually bulges the shingle, the resistance to the load is immediately distributed between the tabs 74 and 75 and nails 77, 78, 79 and 80. This force is then substantially equalized and the tabs 74 and 75 are subjected to forces which in a great many instances, are greater than forces required to tear a shingle. If these forces of load 73 are too strong, then they will tear the tabs 74 and 75 at their juncture with the main body of the shingle or they will pull the tabs out from under shingles 71 and 72. The amount of bulge of the shingle 70 in Fig. 9 is illustrated in a ratio to the bulge shown in Fig. 5 with the same load in each case, but this bulge in Fig. 9 is due to the stretching of the internal structure of the shingle and to any tearing of the tabs 74 and 75. There is no free predetermined length of movement of the tabs before being locked against further movement. Tabs 74 and 75 are locked against movement at the time of being laid on the roof or siding.

Thus, it will be seen that with the improved shingle the distribution of load forces as actually applied to tabs 27 and 28 of Figs. 1 and 4, are below the forces required to tear a shingle, while the forces of load 73 on tabs 74 and 75 of shingle 70 in Fig. 8 are usually greater than the forces required to tear a shingle.

With this type of assembly as noted in Fig. 8, and the load immediately distributed to the four corners, the shingle then becomes a so-called "indeterminate" structure and only the stretching of the internal structure of the shingle permits bulging of the shingle to have equilibrium

develop between the four fastening points or members.

The value of the improved design of shingle herein is graphically shown by the stress diagrams, illustrated in Fig. 6 for the assembly of Fig. 4, and in Fig. 10 for the prior type of shingle assembly as noted in Fig. 8. The ratios of the lengths of the chords are in proportion to the stresses. It will also be noted that the amount of shingle deflections shown in Figs. 5 and 9 are exaggerated somewhat to show their differences. However, the differences between the deflections results in a large reduction of tearing stress on tabs 27 and 28 as assembled in Fig. 4.

Referring now particularly to Figs. 6 and 10, the loads 66 and 73 noted in Fig. 5 and in Fig. 9, are the same, and are diagrammed by the line 86—87 for assembly in Fig. 4 and also by the same numbers in Fig. 9, for the assembly in Fig. 8. The distribution of load forces on tabs 27 and 28 for assembly in Fig. 4, are shown by line 88—89, and by line 90—91 in Fig. 10 for the assembly of shingles in Fig. 8. It will be noted that the line 88—89 is considerably less than the line 90—91 and this reduction is mainly due to the predetermined limited movement of the tabs in the supplemental recesses.

In order to show the mathematical differences in the tearing forces, reference is now made to Fig. 11, and it will be explained in connection with the assemblies shown in Figs. 4 and 8, commenting first on the forces of Fig. 8. Take for example the case of a specific shingle shown where the distance from the load 73 for Fig. 9 and 66 for Fig. 5 to the point of contact of the lock is about 8.5" in actual construction of the shingle. This is shown on the diagrammatic sketch of Fig. 11 as line 96—97. Consider first, the case of no movement in a supplemental recess, Fig. 8, and assume because of the upward or outward thrust of the loads and the elastic properties of the shingle, it is stretched about $\frac{1}{2}$ " or about 0.031", represented by line 96—98.

Consider next, the case of the movement of $\frac{1}{8}$ " in the supplemental recesses (assembly in Fig. 4) and as represented in Fig. 11 by distance 96—99, there is a corresponding stretching of the shingle by 0.031". The shingle is then represented by line 99—100 and its corresponding deflection by the line 97—100. This results in a substantially less acute angle of deflected shingle with the under roof surface. The tearing force is then in ratio of cotangents of the included angle or

Without movement (Fig. 8):

Cotangent of angle whose cosine is

$$\frac{8.5}{8.531} = 0.99637$$

is equal to 11.7050

With movement (Fig. 4)

Cotangent of angle whose cosine is

$$\frac{8.375}{8.531} = 0.98171$$

is equal to 5.1566

It is therefore evident the tearing force has been reduced by

$$\frac{5.1566}{11.705} \times 100 = 44.05\%$$

a substantial amount. This condition is shown by the graphical stress diagram, Fig. 7, where load 73 or load 66 is shown by the line 101—102 equal 0.5", and the tearing force, without move-

ment, by the line 102—103, equal 5.85" and the tearing force with the limited movement of the weather end of the shingle by line 102—104 equal 2.579", or ratio of 0.4405.

Thus, it will be noted that when the improved type of shingle is employed and a predetermined limited movement of the weather end of the shingle is available, the tearing force is greatly minimized.

In incorporating the features of this invention in the shingle, it has been found that the axes of the supplemental recesses should bear a definite relationship to the fastening means or nails and particularly to nails nearest the supplemental recesses. It has been found during the tests that the axes of the supplemental recesses best serve the purpose of reducing tear of the tabs by being substantially perpendicular to a line drawn between the two nearest fastening nails, such as between nails 59 and 62 on shingles 49 and 50, Fig. 4. With the axes of the supplemental recesses perpendicular to the line between the two nails, it will be noted that the axes in these supplemental recesses are at angles to the axes of the main recesses 29 and 30. It may also be said the axes of the supplemental recesses 31 and 32 are parallel with a line passing through the opposite ends of the shingle 49, one of the ends being where the tabs 27 and 28 are formed. By so forming the axes of the supplemental recesses, there is less likelihood of the tabs being bound against movement through the predetermined limited distance. In the event of using a single tab in the place of two, then the axis of a supplemental recess may be at a slight angle from the above mentioned perpendicular to a line between holding means 59 and 62.

In the laying of the shingles on a roof or on a siding, it has been found from experience that the location of the fastening means or nails 59, 60, 61 and 62 are very satisfactory as noted in the drawing. However, for certain purposes the nails may be positioned differently, and in that case, the means for resisting the load force may vary and the line between the two nails holding means to the weather end of the shingle may not necessarily be perpendicular to the axis of one or more supplemental recesses. However, the axis of the supplemental recess will be at angles to the main recesses.

The types of slits or notches or specially designed recesses are to be noted in Figs. 12 to 17, wherein a slit 106, Fig. 12, may be employed for an interlocking purpose or may be employed for location purposes when laying the shingles. Recess 107 of Fig. 13 is sufficiently wide to allow a predetermined movement of the weather end of the shingle so that the tabs are not required to take too much of the force of the load. The circular recess formation 108 in Fig. 4 also allows relative movement in most any direction. The recesses 109 and 110 of Figs. 15 and 16 are of different structures and have their axes arranged at different angles to the body of the shingle. Recess 111 of Fig. 17 may be employed to cooperate with a like recess in another shingle and may be positioned as desired. Recesses 109 and 110 may be used as notches 34 and 35, depending upon the type and structure of shingle. It will be noted from the foregoing description that the improved shingle herein permits a definite movement of the weather end of the shingle while the wind load is starting and increasing. As this load increases, the weather end of the shingle freely moves for a predetermined

distance and thereafter becomes locked and takes a portion of the load. However, this portion of the load has been found from tests to be less than the values of forces necessary to tear a shingle. It will also be noted that the special type of recesses and notches and their cooperation is such that the distance of travel of the weather end of the shingle before the tabs become locked, is substantially uniform. However, supplemental recesses may have a little greater length when they are not assembled with notches. The improved design of the shingle will meet this type of free predetermined limited movement before the tabs become locked.

It will be understood that various modifications and changes may be made in the preferred form of the invention herein, and such modifications and changes are to be understood as part of this invention, as outlined in the following claims.

The invention claimed is:

1. A flexible shingle being formed within the general outside outline of a rhombus, said shingle having one corner to be exposed to the weather when laid and having a series of tabs with one on each side of the weather corner thereof and being within the general outside outline of said shingle and forming main recesses with the sides of said shingle, said shingle having cut away portions to form smaller supplemental recesses subtended from the inner ends of said main recesses, the longer axes of said supplemental recesses being substantially perpendicular to a line between two points for fastening said shingle to a roof, each of said fastening points being substantially at the shingle corners that are nearest the corner having said tabs formed therein.

2. A flexible shingle being formed within the general outside outline of a rhombus, said shingle having one corner to be exposed to the weather when laid and having a series of tabs with one on each side of the weather corner thereof and being within the general outside outline of said shingle and forming main recesses with the sides of said shingle, said shingle having cut away portions to form smaller supplemental recesses subtended from the inner ends of said main recesses, the longer axes of said supplemental recesses being substantially perpendicular to a line between two points for fastening said shingle to a roof, each of said fastening points being substantially at the shingle corners that are nearest the corner having said tabs formed therein, said shingle also having a relatively small notch formed in each edge of said shingle that has the said tabs formed therein, each of said notches being positioned near each of said fastening points.

3. In a roof structure, a series of courses of shingles, each shingle being formed within the general outside outline of a rhombus and being laid in each course to have a free weather corner and being firmly affixed to the roof substantially at the corners above and nearest said free weather corner and to have said affixed corners substantially abutting like affixed corners in adjacent shingles in the same course, each of said shingles having its free weather corner cut away to form a tab and a main recess with said body on opposite sides thereof, said tabs and said recesses being formed within an outside outline of said shingle, said tabs interlocking with the adjacent shingles of the next lower course relatively near the points of the fastenings of those adjacent

shingles to the roof, each of said shingles having supplemental recesses formed therein and subtending from the inner ends of said main recesses and having the longer axis of each of the supplemental recesses forming an angle with the longer axis of each adjoining main recess, each of said shingles as assembled on the roof structure being positioned to have an edge of each of the adjacent shingles in the next lower course coincide approximately with the intersection of the axes of said main and said supplemental recesses thereby providing spaces substantially equal to the lengths of said supplemental recesses for allowing the free weather corner of each of said shingles to have limited upward movement between the free corner of each shingle and the fastened parts of said adjacent shingles that are engaged by said tabs before said tabs are locked against further movement thereby reducing tearing of said shingle tabs at the base of said main recesses.

4. In a roof structure, a series of courses of shingles, each shingle being formed within the general outside outline of a rhombus and being laid in each course to have a free weather corner and being fastened to the roof at substantially the three corners above said weather corner, the fastened corners nearest said free weather corner substantially abutting like corners of adjacent shingles in the same course, each of said shingles having its free weather corner cut away to form a tab and a main recess with said body on opposite sides of said weather corner, said tabs and said recesses being formed within an outside outline of said shingle, said tabs interlocking with the adjacent shingles of the next lower course relatively near the points of the fastenings of those adjacent shingles to the roof, each of said shingles having supplemental recesses formed therein and subtending from the inner ends of said main recesses and having the longer axis of each of the supplemental recesses forming an obtuse angle with the longer axis of each adjoining main recess, each of said shingles as assembled on the roof structure being positioned to have an edge of each of the adjacent shingles in the next lower course coincide approximately with the intersection of the axes of said main and said supplemental recesses to allow upward relative free movement of said weather corner of said shingle for the length of said supplemental recesses before becoming locked against further movement, each shingle resisting an upward load developed by high speed winds over the surface thereof by first distributing the beginning of the load at said three main fastened points of each shingle and after the movement of said weather corner for the length of said supplemental recesses to redistribute the forces of the load to include pulls on said tabs while maintaining the main forces of distribution on the three main fastening points.
